TOY BOAT

Harold H. Reuther, Wyomissing, Pa.

Application September 23, 1950, Serial No. 12,328

Term of patent 7 years

(Cl. D34—15)

To all whom it may concern:

Be it known that I, Harold H. Reuther, a citizen of the United States of America, residing at 1157 Cleveland Avenue, Wyomissing, in the county of Berks and State of Pennsylvania, have invented a new, original, and ornamental Design for a Toy Boat, of which the following is a specification, reference being had to the accompanying drawings, forming part thereof.

Figure 1 is a top plan view of the toy boat in accordance with my new design.

Fig. 2 is a side elevational view thereof.

Fig. 3 is a front elevational view thereof, and Fig. 4 is a rear elevational view thereof.

I claim:

The ornamental design for a toy boat, as shown.

HAROLD H. REUTHER.
